UNITED STATES PATENT OFFICE.

FREDERICK C. OVERBURY, OF HILLSDALE, NEW JERSEY, ASSIGNOR TO THE FLINT-KOTE COMPANY, INC., OF BOSTON, MASSACHUSETTS, A CORPORATION OF MASSACHUSETTS.

MACHINE FOR MAKING SHINGLE-STRIPS.

1,394,342.

Specification of Letters Patent.

Patented Oct. 18, 1921.

Continuation of application Serial No. 386,579, filed June 4, 1920. This application filed October 23, 1920. Serial No. 412,905.

To all whom it may concern:

Be it known that I, FREDERICK C. OVERBURY, a citizen of the United States, residing in Hillsdale, in the county of Bergen and 5 State of New Jersey, have invented certain new and useful Improvements in Machines for Making Shingle-Strips, of which the following is a specification.

This application is a continuation of an 10 original application for United States Letters Patent filed by me on July 14, 1915, Serial No. 39,883, and allowed under date of April 14, 1919; which application was renewed after being allowed to lapse under 15 date of June 4, 1920, Serial No. 386,579 and now stands allowed under date of June 4, 1920.

This invention relates to a machine for producing roofing strips and more particularly to a mechanism adapted for producing flexible waterproof roofing strips having designs cut out along one edge of the strip, these strips being connected to the roof in overlapping courses to expose the edges from 25 which the cutouts are made.

Among the salient objects of the invention are to provide a machine by which a plurality of roofing or shingle strips can be produced from an ordinary sheet of prepared 30 roofing, and in such a manner as to utilize the original outer or selvage edges of the sheet as the lower or exposed edge of the roofing strip when laid. Other objects of the invention are to provide a machine for automatically cutting and removing the cutout 35 portions along the edge of the strip, the cutouts being entirely severed from the sheet before forcing them out of the plane of the main body of the sheet; to provide means for automatically ejecting the cutouts of the strip when severed; to provide a construction 40 in which a continuously rotating head can be employed to produce a plurality of the strips, the cutout at one edge; however, 45 being independent of the cutout at the opposite edge; to provide a construction in which removable knives can be employed and the entire mechanism readily changed or adjusted; and in general to provide an improved machine for producing roofing of the 50 character referred to and rewinding the strips as formed.

In the drawings:

Figure 1 is a side elevation of a machine embodying my invention. 55

Fig. 2 is a vertical cross section through the portion of the mechanism which carries the cutter heads.

Fig. 3 is a front elevation of the mechanism shown in Fig. 2. 60

Fig. 4 is an enlarged side elevation of one of the cutting knives.

Fig. 5 is a cross section on the line 5—5 of Fig. 4, looking in the direction of the arrows. 65

In the particular embodiment of my invention shown in the drawings, I employ a power driven machine which is provided with one or more cutter rolls or heads 1, each of which carries a plurality of cutting members 2, adapted upon rotation of the cutter head to completely sever strips from the marginal portion of a continuously advancing sheet 3 of flexible roofing, which is fed over an idler roll 4. As the sheet passes 70 over the idler roll, the cutting members 2 are brought against the portion of the sheet which is passing over the face of the roll, and cut out strips from the marginal portions thereof. The sheet is drawn across the 75 idler roll by means of drawing off rolls 5 and 6, and after passing through the drawoff rolls, it is conducted across a feed bed to a pair of slitting rolls 7 and 8, after which it is rewound into a roll 9. 80

The idler roll 4 is mounted in the side frames 11 and 12, which are connected at their lower ends by a series of ties or cross braces 13. Adjustably mounted in the end plates 11 and 12 is a carrier roll 14 held in 85 frictional contact with the idler roll 4 by means of an adjusting screw 15, which raises or lowers it accordingly as the worm gear 16 is adjusted to the right or left. The drawing off rolls 5 and 6 are mounted in the supplemental frame members 17 and 18 which are secured by bolts 19 and 20 to the end plates 11 and 12, and the roll 5 is spring-pressed toward the roll 6 by the action of springs 21 and 22 so as to have sufficient 90 frictional contact with the sheet to draw it along across the idler roll. 100

There are preferably a pair of the cutting heads, 1 each carrying a plurality of the

cutting members 2 and adapted to operate upon the opposite edges of the double width sheet, and the cutter heads are bolted to a shaft 23, which is journaled in the end plates 5 11 and 12, and is provided at one end with a gear wheel 24. The end plates 11 and 12 have bearings 25 in which the main drive shaft 26 is journaled, this shaft being provided at one end with a bolt wheel 27 and at 10 its opposite end with a gear wheel 28. The connection between the gear wheel 28 on the drive shaft and the gear wheel 24 on the cutter head shaft is as follows:

Mounted on the end plate 11 is an intermediate gear 30 which meshes with the gear wheel 28 and a gear wheel 31 secured to the carrier roll shaft 32. This last mentioned gear wheel is connected to a second intermediate gear wheel 33 by means of intermediate spur gears 34 and 35, which are mounted on a swinging arm 36. The axis about which this arm swings is coincident with the axis of the gear wheel 33, and at its lower end the arm is provided with a slot 37, 25 through which projects a bolt 38 provided with a locknut 39. Upon loosening this nut 39 the arm 36 can be swung so as to adjust the spur gears 34 and 35 to compensate for the adjustment in taking up the wear on the 30 idler roll. At its upper end the second intermediate gear wheel 33 meshes with the gear wheel 24 of the cutter head shaft 23, and through the train of gears above described, the shaft 23 is driven from the 35 shaft 26.

The drawoff rolls 5 and 6 are also driven from the shaft 26, the rolls being provided with intermeshing gears 41 and 42 which are driven from the intermediate gear wheel 40 33 as follows: Mounted on the supplemental frame 17 is an intermediate gear 43, which meshes with a gear 42 and also with a gear wheel 44, the latter as shown in Fig. 3, being sufficiently thick to intermesh with both 45 the gear wheel 43 and the intermediate gear 33 so that the movement of the latter is imparted through the gears 44, 43, 42 and 41 to the drawing off rolls. The proportioning of the chain of gears above described is 50 such that the drawing off gears pull the sheet across the idler roll 4 at a speed so related to that of the cutter head roll that the knife members of the latter will completely sever the pieces from the marginal edges of the 55 sheet without any danger of tearing, it being understood that the surface of the idler roll which serves as a bed for the cutting knives is of such material as to permit the knife blades cutting through and making a clean 60 cut in the roofing sheet.

The detailed construction of the cutting members is shown in Figs. 4 and 5, and comprises parallelly arranged knife members 46 and 47, which are spaced to receive a 65 spring member 48. The portions of these

cutting members which are brought into engagement with the feed roll 4 are beveled to provide cutting edges 49 and 50, the total width between the cutting edges being the desired width of the strip which is to be 70 removed from the sheet. At their ends nearest the center of the sheet, the space between the knife members 46 and 47 is closed by a short transversely extending knife member 51, which will sever the end of the 75 oblong portion 45, the sides of which are cut by the knife members 46 and 47. The knives 46 and 47 are secured to the respective arms 52 of the cutter head by means of bolts 53 and 54 extending through slots 55 80 and 56.

In order to prevent the cutout portions 45 from clogging up the cutter knives, the spring 48 is so mounted that its outer edge 57 normally projects beyond the plane of 85 the cutting edges 49 and 50. When the latter are in engagement with the sheet the spring will thus be compressed, but as soon as the cutter knives pass out of engagement with the sheet, the spring will normally return to its position beyond the plane of the cutter knives and eject the cutout portion 45 as shown in Fig. 5. The sheet is then fed forward from the draw off rolls to the slitting rolls 7 and 8 which sever it down 95 the center. If desired, the slitting rolls can be provided with a mutilated portion 59, which at spaced intervals in the sheet will leave narrow connecting portions for holding the two strips together, it being understood that in this case the user would completely sever the two strips by simply cutting the narrow connecting portions. The completed product, which comprises two of the strips each having a plane edge and a 100 coated edge, is then rewound in a roll 9 upon a shaft 60, which shaft as well as the slitting rolls 7 and 8 can be driven by any suitable connection (not shown) to the main drive shaft 26.

The shaft which carries the cutter heads is mounted in sliding blocks 61 and 62 which are suspended from a lifting shaft 63 by means of links 64 and 65, and in addition to the adjustment provided for the carrier roll, the position of the cutter head relative to the idler roll can be adjusted by means of a hand wheel 66, which has a screw threaded engagement with the lifting shaft adjusting member 67.

It will be noticed that the action of the two cutter heads is simultaneous but that the mounting of the cutter knives of each head is independent of that of the cutting knives of the other head. This permits the 125 knives of either head being adjusted or replaced without changing the knives on the other head and it is therefore possible on the machine to simultaneously produce from the same double width roll of roofing a pair 130

of strips having different designs cut from their exposed edges, the strips when used being laid in overlapping courses with the cutout edges forming the lower or exposed edge of the strip.

Moreover, the use of the independent cutter heads permits the cutout or exposed edges of the strips being so formed that the original outer edge of the roofing sheet can be retained as the lower or exposed edge of the roofing strips when laid. Also in rewinding the strips, the edges having the slots 68 and 69 are at the outer edges of the roll while the abutting edges of the two strips, if rewound in a single roll, are the edges, which when laid, will be concealed and the machine is therefore capable of producing a new and improved type of roofing package.

While I have shown and described in detail a machine embodying the various features of my invention, I do not desire to limit the later to the details of construction described nor in any manner except as specified in the appended claims.

I claim as my invention:

1. In a machine for producing from a single strip a pair of roofing strips, in roll form, having their original longitudinal edges cut out in design for simulating a plurality of individual shingles and in combination, a pair of rolls for advancing the strip, a cutting bed in advance thereof over which the strip is fed from a source of supply, a rotating cutter whose axis is located in a vertical plane between the bed and advancing rolls, said cutter comprising spaced apart heads, each including a plurality of radially projecting arms and cutting blades associated with the arms and an additional cutting edge extending longitudinally of the feed of the sheet, and a slitter mechanism.

2. In a machine for continuously feeding a double width strip of flexible roofing material, cutting out designs in the original lengthwise edges thereof for simulating individual shingles, slitting the strip through the middle lengthwise thereof and reeling the notched and slitted strip and in combination, a pair of rolls for advancing the strip, a cutting bed over which the strip is fed

from a source of supply, a rotating cutter comprising spaced apart heads, each including a plurality of radially disposed cutting devices having parallel spaced apart cutting edges extending transversely of the direction of feed of the strip with their outer end portions intersecting the longitudinal edges of the strip and an edge extending parallel with the feed of the strip and located between the inner end portions of the parallel spaced apart cutting edges, a slitter located in a vertical plane midway between the cutter heads, and coacting with the strip midway between the lengthwise edges thereof for slitting the strip as it is fed by the advancing rolls and a reel in the rear of the slitter for reeling the slitted and notched strip into a roll.

3. In a machine for producing from a single sheet, a pair of roofing strips having their original lengthwise edges cut out in design for simulating a plurality of individual shingles and in combination, means for advancing the sheet, a support over which the sheet is fed, a rotating cutter located in a vertical plane between the support and advancing means, said cutter comprising spaced apart heads, each including a plurality of radially projecting arms and cutting blades associated with the arms and an additional cutting edge extending longitudinally of the feed of the sheet, and a slitter mechanism.

4. In a machine for producing from a single sheet, a pair of roofing strips having their original lengthwise edges cut out in design for simulating a plurality of individual shingles and in combination, means for advancing the sheet, a support over which the sheet is fed, a rotating cutter located in a vertical plane between the support and advancing means, said cutter having parallel spaced apart cutting edges extending transversely of the direction of the feed of the sheet, the outer ends of the edges intersecting the longitudinal edges of the sheet, and a slitter located in the rear of the advancing mechanism.

5. In a machine for continuously feeding a double width strip of flexible roofing material, cutting out designs in the original lengthwise edges thereof for simulating shingles, slitting the strip through the middle lengthwise thereof, and in combination, means for advancing the strip, a cutting bed over which the strip is fed from a source of supply, a rotating cutter having a plurality of radially disposed cutting devices having spaced apart cutting edges extending transversely of the direction of the feed of the strip and an edge extending longitudinally of the feed of the strip and a slitter for slitting the strip as it is fed forwardly.

6. In a machine for producing from a single sheet, a pair of roofing strips having

- their original lengthwise edges cut out in design for simulating a plurality of individual shingles, and in combination, means for advancing a sheet, a support over which the sheet is fed, a rotating cutter located between the support and advancing means, said cutter being provided with a plurality of radially projecting arms, and cutting blades associated with the arms and an additional cutting edge extending longitudinally of the feed of the sheet and a slitter mechanism.
7. In a machine for producing from a single sheet a pair of roofing strips having their original lengthwise edges cut out in design for simulating a plurality of individual shingles, the combination with means for feeding the sheet, of a support over which the sheet is fed, a rotating cutter located between the support and feeding means, said cutter having supporting members and cutting members associated with the supporting members and an additional cutting edge extending longitudinally of the feed of the sheet, and a slitter mechanism.
8. In a machine for producing from a single sheet a pair of roofing strips having their original lengthwise edges cut out in design for simulating a plurality of individual shingles, the combination with means for feeding the sheet, of a support over which the sheet is fed, a cutter located between the support and feeding means, said cutter having a plurality of supporting members and cutting members associated with the supporting members and an additional cutting edge extending longitudinally of the feed of the sheet, and a slitter mechanism.
9. In a machine for producing from a single sheet a pair of roofing strips having their original lengthwise edges cut out in design for simulating a plurality of individual shingles, the combination with means for feeding the sheet, of a support over which the sheet is fed, a rotating cutter located between the support and feeding means, said cutter having supporting members and cutting members associated with the supporting members and an additional cutting edge extending longitudinally of the feed of the sheet, and a slitter mechanism.
10. In a machine for producing from a single sheet a pair of roofing strips having their original lengthwise edges cut out in design for simulating a plurality of individual shingles, the combination with means for feeding the sheet, of a support over which the sheet is fed, a rotating cutter located between the support and feeding means, said cutter having supporting members and cutting members associated with the supporting members and an additional cutting edge extending longitudinally of the feed of the sheet, and a slitter mechanism.

FREDERICK C. OVERBURY.
